SPLITTING MECHANISM

John J. Kindle, Buckley, and Eldon W. Young,
Copalis Crossing, Wash.

Application December 20, 1941, Serial No. 423,802

1 Claim. (Cl. 144—194)

Our invention relates to a splitting mechanism which is particularly adapted for splitting blocks of wood as in the production of shingles or shingles of the split type and useful in roofing and wall covering. It will be apparent that the invention has many other uses in splitting block material.

An important object of our invention is the provision of a vertically disposed knife blade to which blocks to be split are conveyed, and during which conveyance, means operate upon the block to align it with respect to the blade so that the split may be obtained in a predetermined desired upright plane.

Another object of our invention is to provide a vertically disposed knife blade to which blocks of material to be split are conveyed and presented with force to accomplish a splitting action, which conveying means will also carry the split portions of the block past the knife for subsequent disposal.

A further object of the invention relates to the provision in a splitting mechanism in which a block of material to be split is presented to a knife blade, and in which mechanism a pair of synchronized presser members operate upon the block, during its conveyance to the knife, to position it to insure that the knife will split it in a desired and predetermined plane through the block.

Still another object of our invention relates to the provision, in a splitting mechanism wherein a block of material is presented to a vertically disposed knife blade, of means pressing against the block as it is presented to the knife blade to align it therewith and which means are resiliently pressed and synchronized together so that outwardly exerted pressure against the resiliency of one member will be translated to the other member for the purpose of aligning the block passing therebetween.

Other objects and advantages of the invention will be more apparent during the course of the following description.

In the drawings accompanying this specification, and in which like numerals designate like parts throughout the same, we have illustrated a preferred and a modified form of our invention. It will be apparent that changes and alterations in material, size, shape and general arrangement of parts and the like may be made within the scope of the subjoined claim without departing from the principles of the invention.

Figure 1 is a side elevational view of our splitting mechanism,

Figure 2 is a plan view of the device of Figure 1, shown somewhat enlarged, with portions omitted for convenience of illustration.

Figure 3 is a vertical sectional view taken longitudinally through the machine of Figure 2, and with portions shown in elevation for clarity of illustration.

Figure 4 is a horizontal sectional view taken on a plane lying below that of the showing of Figure 2, and illustrating a block of material to be split as it appears in passing through the mechanism.

Figure 5 is a sectional view taken on line 5—5 of Figure 2.

Figure 6 is a sectional view taken on line 6—6 of Figure 2.

Figure 7 is a sectional view taken on line 7—7 of Figure 2.

Figure 8 is a perspective view illustrating a modified form of presser means employed in our splitting mechanism, and

Figure 9 is a fragmentary plan view illustrating the manner in which the device of Figure 8 is associated with the knife blade that we employ for the splitting operation.

The numeral 10 designates a supporting leg of our work table which also has stub legs 12 supported by wheels 13. Longitudinally of the machine, and associated with the upper ends 30 of legs 10 and 12 are a pair of frame members 14 and 15 that extend throughout the length of the machine in spaced apart relation from each other. An intermediate shelf 16, that may be seen in Figures 1, 3, 5, 6, and 7, is supported between rails 14 and 15. An inverted U-shaped housing 18 is attached to the upper face of the members 14 and 15, throughout a portion of their length. A vertically disposed knife blade 20 is shown secured at 21 to shelf 16 and extending upwardly between the walls of the housing 18, being supported at its upper end by the horizontal wall 22 of the housing.

Knife blade 20 is disposed substantially medial to the housing 18.

45 A forwardly extending flange or plate 24 of the housing 18 provides bearing or journal means for the upper ends of shafts 26. The lower ends of the shafts 26 are also journaled in clips 27 which are attached to the members 14 and 15. 50 Extending rearwardly from each shaft 26 are the resilient presser members 30 which are resiliently and constantly urged toward each other by means of the springs 32 mounted upon bolts 33 that attach at one end to the member 30 and 55 pass through angle clip 34.

The upper ends of the shafts 26 each carry gear segments 36 that are meshed together to synchronize the movement of the wings 30.

A pair of endless feed chains 38 pass over sheaves or sprockets as 39 on a shaft 40 and sprockets 41 on a shaft 42 behind the knife 20. These chains are provided with upstanding lugs 44 which engage a block of material as B to convey it to the knife 20.

The chains or endless feed elements are spaced apart slightly to pass on either side of knife 20 and thereby carry the split material away from the knife after the splitting operation has been accomplished. Power is applied to the feed element from the motor 46 by means of a belt 47, and a fly wheel 48. Wheel 48 rotates the shaft 49 and the pinion 50 which is in mesh with gear 51 to produce rotation of the drive shaft 42 in the usual manner.

In Figures 8 and 9 an alternative form of presser member is employed in which shafts 66 are provided with cam portions mounted thereon eccentric to the axis of the shafts. The cam portions are indicated by the numeral 68 and function in the same manner as members 30. The upper ends of shaft 66 are synchronized together with gear segments such as 36, and the lower ends of the shafts are each provided with a lever 70 that are joined by a spring 72, which positively, although resiliently, urges the cam portions toward each other.

In the operation of the device, a block of wood is placed by an operator upon the feed chains 38 so that a lug 44 engages the following end of the block and forces it forwardly toward the vertically disposed knife blade. As the block passes into the space between the presser members 30, or the members 68 in the modified form of the invention, engagement is usually effected with one or the other of the members, or it may be effected with both members simultaneously. The members, being synchronized together, tend to dispose the block of material to be split intermediate of them in a manner to present it medially to the splitting knife. As the block of ma-

terial under the urging of lug 44 engages the sloping or undercut edge 23 of the knife, the knife enters the wood and produces a fracture that tends to follow a natural line of cleavage therebetween. Half of the block, approximately, will pass on each side of the blade, and be conveyed on through the housing 18 and out the tail end of the mechanism. It is desirable to provide means in a splitting mechanism to properly align the block to be split during conveyance so that the split will be effected in a predetermined upright plane in the block. That is the function of members 30 or 68.

In preparing the material for the splitting operation accomplished in our mechanism it is customary to shape them to an approximate standard, and thereafter it is desirable that they be split approximately equally down the center, or in any other desired plane, so that a uniform product will result, even despite variations in grain structure and the like.

Splitting operations may be carried on in our mechanism with continuity and at high speed, and uniformity in the product is an important characteristic that has heretofore been unable to be attained in split shaves, which is one use in which the invention is very practical of adaptation.

We claim:

In a splitting mechanism wherein a block of material to be split is presented to a vertically disposed knife blade, means for aligning said block with respect to said blade and comprising: a pair of opposed cylindrical presser members each mounted to swing about a vertical axis eccentric of the axis of their cylindrical contour, the major portion of said cylindrical presser members extending knifeward from said axis of rotation, means for resiliently urging said presser members toward each other, and means operable to retract either presser member against its bias when pressure is applied to the other of said presser members.

JOHN J. KENDLE.
ELDON W. YOUNG.
